UNITED STATES PATENT OFFICE

WALTER E. HOLLAND, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA

METHOD OF ASSEMBLING ELECTRODYNAMIC SOUND REPRODUCERS

Application filed January 28, 1930. Serial No. 423,973.

This invention relates to improvements in methods of assembling electrodynamic sound reproducers.

Sound reproducers of this type employ a diaphragm having attached thereto a voice coil which operates within a restricted gap between pole pieces either permanently magnetized or having associated therewith a second coil for setting up a magnetic field. 10 In operation, the voice coil is energized by signals from the source, and the resultant movement of the coil in the magnetic field actuates the diaphragm and effects a reproduction of the signal. By reason of the restricted character of the space within which the voice coil operates and the limitations imposed by the mechanical structure, it has been a relatively difficult operation to properly center the voice coil in the gap between 15 the pole pieces, a condition which is essential to a proper operation of the reproducer.

The principal object of the present invention is to provide a simple and accurate method for centering the voice coil in the gap between the pole pieces within which it 20 operates, as set forth above.

In the attached drawing:

Figure 1 is a diagrammatic sectional view illustrating enough of the assembly of an 25 electrodynamic sound reproducer to afford a thorough understanding of the present invention, and

Fig. 2 is a wiring diagram further illustrating the invention.

With reference to Fig. 1 of the drawing, 30 1 is the diaphragm of an electrodynamic sound reproducer, and 2 is the diaphragm-actuating voice coil supported upon a hollow cylindrical foundation projecting from the apex portion of the diaphragm. 3 and 4 are pole pieces forming a restricted gap within which the coil 2 operates, and 5 is a field coil, which surrounds the pole piece 4 as illustrated. In accordance with the 35 invention set forth in the copending United States application Serial Number 375,848, the coil 2 in the present instance is maintained in a properly adjusted position within the gap between the pole pieces by se- 40 curing the diaphragm, through the medium

of a screw 6 and a flexible integral web 7 at the apex end of the conical diaphragm, to the end of the pole piece 4.

I have discovered that the operation of centering the coil 2 between the pole pieces 55 may be materially facilitated and simplified by energizing the coils, preferably under conditions approximating those of actual service in signal reproduction. I have found, for example, that by energizing the field 60 coil 5 from a suitable source of potential, and by then subjecting the coil 2 to the effect of an oscillating current, preferably of a low frequency, the coil 2, if left free, will 65 be made to center itself within the gap between the pole pieces 3 and 4. In assembling the reproducer, therefore, the screw 6 or other means for maintaining the coil in adjusted position may be rendered temporarily inoperative by removal or loosening 70 and the coils energized as specified, with the result that the coil 2 will center itself within the gap and may then be secured in this centered position by tightening the screw 6 while the coil is oscillating, or by rendering 75 effective the equivalent means for retaining the coil in the proper adjusted position. In this instance, during the centering operation, the diaphragm is left free to move about in accordance with the movement of the voice coil.

A simple and effective method for conducting the operation is to connect the reproducer, where intended for radio reception, in the circuit of a radio receiver and 80 to operate the latter at a relatively high volume, thereafter tightening the screw or rendering the anchoring means operative to retain the coil in the centered position which it will assume upon energization of the coils. 85

In the diagrammatic view of Fig. 2, the voice coil 2 is shown connected in circuit with an oscillator 8 producing, say, 60 cycle alternating current, while the coil 5 within 90 whose field the coil 2 is positioned is connected to a source 9 of direct current, this representing an electrical circuit which will be effective in the practice of my invention. By utilizing a current of relatively low frequency for energizing the coil 2 during ad- 100

justment, assurance is had that under normal operating conditions in actual service there will be no contact between the coil and the pole pieces with a resultant production of extraneous noise.

In another successfully employed method of assembly employing the principle, the diaphragm is secured in its supporting frame or housing with the coil 2 approximately centered between the pole pieces but with the screw 6 unsecured. The diaphragm securing means consists in the present instance of screws 10 which pass through and secure to the frame 11 the flexible edge portion 12, which edge portion may be an integral part of the diaphragm or an annulus of soft leather or the like secured to the diaphragm. After tightening the screws 10, the coils 2 and 5 are energized as set forth above, which results in an oscillation of the coil 2 between the pole pieces. If the coil 2 is properly centered, it oscillates freely and without contact with the pole pieces regardless of the volume of the oscillating energizing current, and the screw 6 may then be tightened to secure the coil in position. If the coil 2 does not oscillate freely, a proper adjustment of the coil in its gap may be obtained by exerting transverse pressure on the diaphragm and varying the point at which the pressure is applied until free oscillation of the coil within the gap is obtained, after which and while the said rectifying pressure is still effective the screw 6 is tightened to secure the coil in the adjusted position.

I claim:

1. The method which consists in establishing a magnetic field through the medium of closely positioned pole pieces, locating a coil within the gap between said pole pieces, effecting an axial oscillation of the coil by energizing the coil from a source of alternating current, and fixing the axis of said oscillation while the oscillation is in progress.

2. The method which consists in establishing a magnetic field through the medium of closely positioned pole pieces, locating a coil within the gap between said pole pieces, energizing the coil from a source of alternating current to thereby effect centering of the coil within the gap, and securing said coil in the centered position.

3. The method which consists in establishing a magnetic field through the medium of closely positioned pole pieces, locating a coil within the gap between said pole pieces, effecting an axial oscillation of the coil by energizing the coil from a source of alternating current, thereby adjusting the coil within the gap to afford freedom of oscillation without contact with the pole pieces, and transversely fixing the coil in the adjusted position.

4. The method of centering the diaphragm-actuating coil of an electrodynamic speaker within its field gap, which consists in energizing the said actuating coil to effect an oscillation of the actuating coil in the magnetic field, and anchoring the actuating coil against transverse movements during said oscillation.
